CHRISTMAS CARD DISPLAY RACK

Henry Karr, 229 N. 13th St., Philadelphia, Pa.

Filed June 23, 1960, Ser. No. 61,091

Term of patent 14 years

(Cl. D80—9)

FIG. 1 is a front elevational view of a Christmas card display rack embodying my new design;

FIG. 2 is a rear elevational view thereof; and

FIG. 3 is a top plan view thereof.

The heavy shaded areas represent a contrast of colors.
I claim:

The ornamental design for a Christmas card display rack, as shown and described.
